BATH BRUSH OR SIMILAR ARTICLE

Laurence M. Atwood, Dallas, Tex.

Application July 13, 1953, Serial No. 25,889

Term of patent 14 years

(Cl. D9—2)

To all whom it may concern:

Be it known that I, Laurence M. Atwood, a citizen of the United States, residing at Dallas, Dallas County, Texas, have invented a new, original, and ornamental Design for a Bath Brush or Similar Article, of which the following is a specification, reference being had to the accompanying drawing, forming a part hereof.

The dominant features of my design reside in those portions shown in full lines.

I claim:

The ornamental design for a bath brush or similar article, substantially as shown and described.

LAURENCE M. ATWOOD.
